CLAIM

The ornamental design for an accessory interface node as shown and described.

DESCRIPTION

FIG. 1 is a perspective view of an accessory interface node showing our new design in a position of use on the rear of an accessory;

FIG. 2 is an enlarged view of a portion of FIG. 1;

FIG. 3 is a front elevational view of the accessory interface node, shown on the rear of an accessory;

FIG. 4 is a right-side elevational view of the accessory interface node, shown on the rear of an accessory;

FIG. 5 is a left-side elevational view of the accessory interface node, shown on the rear of an accessory; and,

FIG. 6 is a top plan view of the accessory interface node, shown on the rear of an accessory.

The dash-dot-dash broken lines in FIG. 1 illustrate the perimeter of a portion of the accessory interface node that is shown enlarged. The dash-dot-dash broken lines form no part of the claimed design. The broken lines illustrate environmental subject matter that forms no part of the claimed design.
